FLOOR WAX APPLICATOR

Oswald L. Rugaard, Ridgefield Park, N. J., assignor of fifty per cent to John A. Earl, Leonia, N. J., and fifty per cent to Frank Roos, Englewood, N. J.

Application March 3, 1941, Serial No. 381,564

3 Claims. (Cl. 91—25)

My invention relates to improvements in wax applicators, and the primary object of the invention is to provide a device of this character in which the operating mechanism is entirely enclosed, and which is of a simplified and less expensive construction, and which is especially arranged to facilitate and economize in the application of wax to a floor or other surface.

Other important objects and advantages of my invention will be apparent from a reading of the following description taken in connection with the appended drawings, wherein for purposes of illustration I have shown a preferred embodiment of my invention.

In the drawings:

Figure 1 is a general front perspective view of the embodiment.

Figure 2 is a fragmentary left hand side elevational view thereof.

Figure 3 is a fragmentary enlarged side elevational view of the hand grip portion.

Figure 4 is a vertically contracted enlarged longitudinal sectional view taken through Figure 1 along the line 4—4 and looking in the direction of the arrows.

Figure 5 is an enlarged horizontal sectional view taken through Figure 1 along the line 5—5 and looking in the direction of the arrows.

Figure 6 is a top plan view of the combined handle and reservoir.

Figure 7 is a bottom plan view of the lower end of the hand grip portion.

Referring in detail to the drawings, the numeral 5 generally designates the applicator which may comprise a generally conventional applicator head including a transversely elongated relatively rigid plate 6 having upturned edges 7, with a felt or other suitable material applicator body 8 arranged across the bottom of the plate 6 and having its edges overturned around the projections 7 in an inward direction and held down in place by spring bails 9 and 10 mounted on brackets 11 attached to the plate 6. Pivoted at 12 on the said brackets are the lower ends of upwardly converging bars 13 and 14 which are rigidly secured to diametrically opposite sides of the tubular valve body 15 which is threaded on the lower end of the combined handle and fluid wax reservoir which is generally designated 16.

In the present instance the valve body 15 includes the beveled annular flange 17 at its lower end constituting a liquid wax nozzle for guiding the stream of wax released by the valve onto the floor in rear of the applicator head, as indicated in Figure 2 of the drawings. Above the nozzle 17

is the partition 18 which is provided with a central opening terminating in a valve seat 19, the interior of the element 15 being threaded at 20 to accept the lower end of the combined reservoir and handle 16, as shown in detail in Figure 4 of the drawings. A mushroom type valve 21 is positioned relative to the valve seat 19 and is connected on the lower end of the valve operating rod 22 which extends through the opening in the partition 18 and up through the entire length of the combined reservoir and handle 16. The rod 22 has a stop pin 23 retaining a washer 24 which directly engages the upper end of a helical expanding spring 25 which is compressed and has its lower end engaged with the top of the partition 18, whereby the valve 21 is held normally seated in the seat 19 to close off gravitational discharge of the liquid wax 26 in the handle 16.

The upper end of the combined reservoir and handle 16 is provided interiorly with a diametrical web 27 through the center of which the upper end of the rod 22 slides and is exposed above the element 27 a sufficient distance to enable sufficient depression of the rod 22, in a manner to be described, to completely unseat the valve 21. As indicated in Figure 4 the element 27 is depressed somewhat below the upper end of the handle 16 which is exteriorly threaded as indicated by the numeral 28 and to threadably enter and connect the lower end of the hand grip which is generally designated 30.

The hand grip 30 comprises a tubular elbow 31 which has adjacent its lower end a partition 32 in position to press an annular gasket 33 onto the upper edge of the handle 16 to firmly connect the handle portion 30 with the upper end of the handle and prevent escape of fluid, in this case, the liquid floor wax, from the upper end of the handle. The open upper end of the handle provides the medium whereby the liquid wax is introduced into the handle reservoir 16.

Telescoped in and secured within the upper end of the elbow 31 is a suitable hand grip 34 which may have a cylindrical shape as shown or some other suitable shape.

Between the hand grip 34 and the lower end of the elbow 31 there is formed a vertical slot 35 in the crook of the elbow through which extends the bill portion 36 of a trigger or operating lever which is generally designated 37 which is mounted on a pivot 38 traversing and secured in the sides of the adjacent portion of the elbow, the portion 36 of the lever 37 being suitably curved

and positioned for easy operation by the fingers of the operator when gripping the handle portion 30.

Within the elbow 31 the trigger has a right angularly related suitably curved cam portion 39 which bears operatively upon the upper end of a plunger rod 40 which works in an opening 41 in the center of the partition or web 42 and has below this partition an enlarged head 43 arranged for operative engagement with the upper end of the valve operating rod 22. Above the partition 32 the rod 40 has circumscribed thereon an expanding spring 44 which works between the top of the partition and a washer 45 on the rod 40 and is held in place by a pin 46 thereabove.

As a result of the arrangement described, the combined reservoir and handle 16 being supplied with liquid wax, and the handle portion 30 having been connected in place on the upper end of the handle 16, the operator need only to draw the portion 36 of the lever 37 in an upward direction, as in pressing the trigger of a gun, to cause a discharge upon the floor or other surface being waxed, of a selected amount of the liquid wax. Thereupon the applicator head of the device need only be moved over the floor or other surface to distribute the wax in the ordinary manner.

It will be observed that with all of the operating mechanism with the exception of the lever 37 enclosed and concealed within the main body of the device, there are no parts to catch in objects and become impaired in their operation by engagement with outside objects, and to be subjected to deterioration due to exposure. At the same time, the construction and arrangement of parts set forth above provide for economical manufacture, a reduction and simplification of parts, and a reduction in useless weight, with consequent savings in manufacture and shipping costs. These advantages are entirely apart from and in addition to the obvious mechanical superiority due to the fewness of parts and direct and fool-proof action thereof.

Although I have shown and described herein a preferred embodiment of my invention, it is to be definitely understood that I do not wish to limit the application of the invention thereto except as may be required by the scope of the subjoined claims.

Having described the invention, what is claimed as new is:

1. A wax applicator comprising an applicator head for reciprocation over the surface to be waxed, a combined handle and liquid reservoir connected at its lower end to said applicator head and comprising a tube open at its upper and lower ends, a valve normally closing the lower end of said tube, a valve operating rod enclosed within said tube and connected at its lower end to said valve, a handle portion removably connected to and closing the upper end of said tube, and a manually operable lever on said handle portion, said lever being operable to actuate said rod to open the valve.

2. A wax applicator comprising an applicator head for reciprocation over the surface to be waxed, a combined handle and liquid reservoir connected at its lower end to said applicator head and comprising a tube open at its upper and lower ends, a valve normally closing the lower end of said tube, a valve operating rod enclosed within said tube and connected at its lower end to said valve, a handle portion removably connected to and closing the upper end of said tube, and a manually operable lever on said handle portion, said lever being operable to actuate said rod to open the valve, spring means connected to the lower part of said rod normally holding said valve in closed position.

3. A wax applicator comprising an applicator head for reciprocation over the surface to be waxed, a combined handle and liquid reservoir connected at its lower end to said applicator head and comprising a tube open at its upper and lower ends, a valve normally closing the lower end of said tube, a valve operating rod enclosed within said tube and connected at its lower end to said valve, a handle portion removably connected to and closing the upper end of said tube, and a manually operable lever on said handle portion, said lever being operable to actuate said rod to open the valve, spring means connected to the lower part of said rod normally holding said valve in closed position, a nozzle on the lower end of said tube below said valve, said nozzle being positioned to discharge the liquid wax onto said surface at a point to the rear of said applicator head.

OSWALD L. RUGAARD.
